(74) Attorney, Agent, or Firm — IPLA P.A.; James E. Bame

(57) **CLAIM**

The ornamental design for a pet potty tray, as shown and described.

DESCRIPTION

FIG. 1 is a perspective view of my new design;
FIG. 2 is a front elevation view thereof;
FIG. 3 is a rear elevation view thereof;
FIG. 4 is a left side elevation view thereof, the right side
being a mirror image; and,
FIG. 5 is a bottom plan view thereof.
The broken lines illustrate portions of the pet potty tray that
form no part of the claimed design.
